ROSWELL E. CULLINGS, OF WILKINSBURG, PENNSYLVANIA, ASSIGNOR TO WESTINGHOUSE ELECTRIC & MANUFACTURING COMPANY, A CORPORATION OF PENNSYLVANIA.

VOLTAGE-REGULATING SYSTEM.

1,312,165.

Specification of Letters Patent.

Patented Aug. 5, 1919.

Application filed August 10, 1918. Serial No. 249,354.

To all whom it may concern:

Be it known that I, ROSWELL E. CULLINGS, a citizen of the United States, and a resident of Wilkinsburg, in the county of Allegheny and State of Pennsylvania, have invented a new and useful Improvement in Voltage-Regulating Systems, of which the following is a specification.

My invention relates to voltage-regulating systems and particularly to systems for governing the voltage of supply circuits by controlling the excitation of the generators which are connected to such circuits.

One object of my invention is to provide a regulator that shall respond quickly to any change of voltage in the supply circuit and maintain the voltage of such circuit substantially constant without encountering the contact troubles which are frequently experienced in connection with regulators of this type.

More specifically, my invention embodies a regulator having a main-contact relay connected across a supply circuit to be regulated. A differential relay, which is controlled by the main-contact relay, governs the excitation of the generator which is connected to the supply circuit and is provided with means for rendering the relay quick acting and for preventing relay-contact trouble.

In order to render the differential relay quickly responsive to voltage changes in the supply circuit, resistors are severally placed in series with the differential windings but the circuits including such devices tend to produce excessive arcing and welding of the main-relay contact members and thus prevent satisfactory operation of the regulator.

However, satisfactory operation of the relay may be secured by connecting a condenser across the differential windings of the relay so as to effect a shunt circuit through said resistors across the main-relay contact members. Thus, the differential relay is rendered quick acting by means of resistors which are inserted in series with the differential windings, and the main-contact troubles, which are occasioned thereby, are obviated by connecting a condenser across the differential windings.

In the accompanying drawing, Figure 1 is a diagrammatic view of a regulator system constructed in accordance with my in-

vention, and Fig. 2 is a diagrammatic view 55 of the circuits completed through the windings of the differential relay.

Referring to the drawing, a generator 1, comprising an armature 2, a series field winding 3 and a shunt field winding 4, is 60 connected across a supply circuit comprising conductors 5 and 6. A resistor 7 is connected in series with the shunt winding 4 and is adapted to be shunted by a regulator to be hereinafter described.

A main-contact relay 8 comprises an energizing winding 9, which is connected, through a resistor 10, across the supply conductors 5 and 6, and an armature 11 which is pivotally supported by a pivotally mounted arm 12. A contact terminal 21 is mounted on the arm 12 and is adapted to engage a stationary contact terminal 20 when the arm 12 is retracted by means of a spring 22.

A differential relay 13, comprising windings 14 and 15, an armature 16 and a pivotally mounted arm 16^a, from which the armature is pivotally suspended, is controlled by the main-contact relay 8. The winding 14 of the differential relay 13 is connected 80 across the supply conductors 5 and 6 through resistors 17 and 18, and the differential winding 15 is adapted to be connected, through resistors 19 and 18, across the supply conductors 5 and 6 by means of the contact members 20 and 21 of the main-contact relay 8. The arm 16^a of the differential relay 13 is provided with a contact terminal 23 which is adapted to engage a stationary contact terminal 24, when retracted by means 90 of a spring 25, for completing a short circuit across the resistor 7 which is normally included in the circuit of the shunt field winding 4. Adjacent terminals of the two windings 14 and 15 are connected together, 95 and a condenser 26 is connected across the opposite terminals of the windings. A condenser 27 is connected across the contact members 23 and 24 in order to improve their operation.

Assuming the elements of the system to be in the positions illustrated in Fig. 1 and the differential winding 14 to be energized so as to attract the armature 16 and separate the contact members 23 and 24, then the system will operate as follows. Upon a decrease of voltage in the supply conductors 5 and 6, the spring 22 of the main-contact

relay 8 overcomes the pull exerted by the winding 9 and effects engagement of the contact members 21 and 20 to complete the circuit through the differential winding 15 of the relay 13. Thus, the two windings 14 and 15 are simultaneously energized to neutralize each other and to permit the retraction of the armature 16 by means of the spring 23 for short circuiting the resistor 7 by means of the contact members 23 and 24. Consequently, the excitation of the generator 1 is increased and the voltage of the supply conductors is raised to normal value.

In case the voltage of the supply circuit is raised above normal value, the excitation of the winding 9 is raised so as to overcome the action of the spring 22 and separate the contact members 21 and 20. The separation of the contact members 21 and 20 breaks the circuit through the differential winding 15 of the relay 13 and permits the winding 14 to retract the armature 16 in order to open the short circuit across the resistor 17.

In operating systems of the above character without resistors, similar to 17 and 19, in the circuit of the differential windings 14 and 15 of the relay 13, a considerable time lag was noticed in the operation of the differential relay and, by considerable experimenting, it was noted that the time lag of the relay 13 was substantially obviated by placing equal resistors in the circuits of the two differential windings, equal resistors being required in order to balance the operation of the two windings. The resistors inserted in series with the differential winding increased the speed of the relay but occasioned considerable sticking of the relay contact members and other relay contact troubles, and, after further experimenting with the system, it was discovered that a condenser connected across the two differential windings would substantially obviate the contact trouble which was occasioned by speeding the relay by means of the resistors 17 and 19.

Modifications in the system and arrangement and location of parts may be made within the spirit and scope of my invention, and such modifications are intended to be covered by the appended claims.

I claim as my invention:

1. In a voltage regulator, a relay having two differential windings, contact members for governing the operation of the relay,

resistors severally connected in series with said windings for increasing the speed of operation of the relay, and a condenser for establishing a shunt circuit through the windings to prevent contact-terminal arc- 60 ing and sticking.

2. In a voltage regulator, a relay having two windings, means comprising contact members for constantly energizing one of said windings and for intermittently energizing the second winding, and a condenser connected across the windings to prevent contact-terminal sticking and arcing. 65

3. In a voltage regulator, a relay having two differential windings, means comprising 70 contact members for constantly energizing one of said windings and for selectively energizing the second winding in accordance with the voltage obtaining in a supply circuit, and a condenser for connecting the 75 two windings in a closed circuit to prevent sticking of the contact terminals.

4. In a voltage regulator, a relay having two differential windings, resistors severally connected in series with said windings for 80 increasing the speed of the relay, and a condenser for connecting the two windings in a closed circuit to prevent relay contact trouble.

5. In a voltage regulator for a supply 85 circuit, a main-contact relay operated in accordance with the voltage obtaining in the supply circuit, a differential relay controlled by the main-contact relay, a condenser connected across the windings of the 90 differential relay, and means controlled by the differential relay for governing the voltage of the supply circuit.

6. In a voltage regulator for a supply 95 circuit, a main-contact relay operated in accordance with the voltage obtaining in the supply circuit, a relay having differential windings and controlled by the main-contact relay, resistors severally connected in series with the differential windings for increasing 100 the speed of the relay, a condenser for establishing a closed circuit through the differential windings to prevent relay-contact trouble, and means controlled by the differential relay for governing the voltage of the 105 supply circuit.

In testimony whereof, I have hereunto subscribed my name this 31st day of July, 1918.

ROSWELL E. CULLINGS.
